Primary Examiner — Darcey E Gottschalk

(57) **CLAIM**

I claim ornamental design for a container closure having tamper-evidence and a cap, as shown and described.

DESCRIPTION

1.-3. Container closure having tamper-evidence and cap
1.1 is a perspective view of a first embodiment of a container closure having tamper-evidence and a cap in a closed condition;
1.2 is another perspective view thereof in an open condition;
2.1 is a perspective view of a second embodiment of a container closure having tamper-evidence and a cap in a closed condition;
2.2 is another perspective view thereof in an open condition;
3.1 is a perspective view of a third embodiment of a container closure having tamper-evidence and a cap in a closed condition; and
3.2 is another perspective view thereof in an open condition. The shapes shown in solid black color in the reproductions
1.1 to **1.2**, **2.1** to **2.2**, and **3.1** to **3.2** represent surface treatment of the claimed design.

1 Claim, 3 Drawing Sheets
